UNITED STATES PATENT OFFICE.

GEORGE B. EHRIG, OF WASHINGTON, DISTRICT OF COLUMBIA.

ROTARY TOOTHBRUSH.

1,340,760.

Specification of Letters Patent. Patented May 18, 1920.

Application filed October 2, 1919. Serial No. 327,846.

To all whom it may concern:

Be it known that I, GEORGE B. EHRIG, a citizen of the United States, residing at Washington, in the District of Columbia, 5 have invented new and useful Improvements in Rotary Toothbrushes, of which the following is a specification.

This invention relates to improvements in rotary tooth brushes and the principal object of the invention is to provide a rotary frame contained in a case with means for rotating the same by a reciprocating handle and provided with means for engaging the brush.

Another object of the invention is to provide means whereby the handle is reciprocated by a movement of the finger or thumb of the user.

The invention also consists in certain other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the 30 several views, and in which:—

Figure 1 is a sectional view of the invention.

Fig. 2 is a section on line 2—2 of Fig. 1.

Fig. 3 is a section on line 3—3 thereof.

In these views 1 indicates the case for containing the rotatable frame and at one end the casing is provided with a reduced part 2. The rotatable frame 3 consists of the disks 4 and 5 connected together by the rods 35

6 which are of square shape in cross section. The disk 4 carries the socket member 7 which is screw threaded to receive the screw threaded end of the shaft 8 of the brush 9 so that the brush and shaft may be detached 40 from the frame whenever desired. The socket member 7 lies within the reduced end 45 of the case and this reduced end is provided

with an opening to receive the shaft 8. A screw threaded bushing or nut 10 is located in the end of the casing and is fixedly connected with the disk 5. A screw threaded shaft 11 passes through said bushing and at its outer end this shaft carries a handle 12 which is adapted to receive the finger or thumb of the user so that said shaft may 50 be moved longitudinally through the case. The inner end of the shaft has swiveled thereto a plate 13 which is provided with notches 14 to receive the rods 6.

It will thus be seen that when the shaft 60 11 is reciprocated the bushing or nut 10 will be rotated so that the frame 3 will be caused to revolve within the case and thus motion will be transmitted to the brush.

In either case the brush will be given a 65 rotary movement by the reciprocating movement of the shaft and handle so that the teeth may be cleansed with but little effort.

It is thought from the foregoing description that the advantages and novel features 70 of my invention will be readily apparent.

I desire it to be understood that I may make changes in the construction and in the combination and arrangement of the several parts, provided that such changes fall within the scope of the appended claims.

What I claim is:—

1. A device of the class described comprising a casing, a rotatable frame therein, said frame consisting of a pair of disks and rods 80 connecting the disks together, a brush, means for connecting the same with the frame, a reciprocating rod carried by the shaft, means for causing the reciprocating movement of the shaft to rotate the frame 85 and a handle on said shaft.

2. A device of the class described comprising a casing, a rotatable frame therein, a brush, means for connecting the same with the frame, a nut in the case connected with 90 the frame, a screw shaft engaging said nut and a handle on the shaft.

In testimony whereof I affix my signature.

GEORGE B. EHRIG.
